UNITED STATES PATENT OFFICE.

JONAS NORTHRUP AND EVERETT S. WOOD, OF HOPEDALE, MASSACHUSETTS, ASSIGNEES TO
WILLIAM F. DRAPER, OF HOPEDALE, MASSACHUSETTS.

LOOM-SHUTTLE.

No. 926,678.

Specification of Letters Patent.

Patented June 29, 1909.

Application filed December 7, 1908. Serial No. 466,205.

To all whom it may concern:

Be it known that we, JONAS NORTHRUP and EVERETT S. WOOD, citizens of the United States, and residents of Hopedale, county of Worcester, State of Massachusetts, have invented an Improvement in Loom-Shuttles, of which the following description, in connection with the accompanying drawing, is a specification, like characters on the drawing 10 representing like parts.

This invention relates to loom shuttles of the type wherein the bobbin is inserted automatically while the loom is working, and it has for its object the improvement of the 15 means for engaging and holding the bobbin in proper position when placed in the shuttle. The heads of bobbins for use in such shuttles are provided with annular projections or rings which fit into upright grooves or 20 notches made in the opposite and inner faces of resilient or spring jaws held in the shuttle body at one end of the bobbin receiving opening thereof, the jaws slightly converging toward their free ends when there is no bobbin between them.

When the bobbin is inserted the rings engage the upper portions of the jaws and deflect or spring the latter apart to permit the bobbin head to pass down into the central 30 portions of the grooves, the latter being curved longitudinally to firmly grasp and hold the rings when seated therein. In endeavoring to overcome breakage of the jaws at the time of bobbin insertion we have found 35 that the metal has been unduly weakened at or near the grooves nearest the shuttle wood, the series of grooves in the jaw heretofore having been made of equal depth from one to the other end of the series. We have overcome 40 this breakage to a very great extent, by making the grooves nearer the base of the jaw of less depth than the other grooves, and in fact the percentage of breakage is thereby reduced to an exceedingly small amount. We 45 have also facilitated the entrance of the bobbin into position between the jaws by providing the upper ends of the grooves with guide-entrances which are flared outwardly and also transversely, and located symmetrically with relation to the grooves, so that the bobbin rings in entering the jaws will not ride or rest upon the ridges or partitions between adjacent grooves.

Figure 1 is a top plan view partly broken 55 out, of the bobbin holding end of a loom

shuttle with one embodiment of our invention applied thereto. Fig. 2 is an inner face view of one of the jaws detached. Fig. 3 is a longitudinal section of the jaw on the line 3-3, Fig. 2.

In Fig. 1 the shuttle-body 1 has a bobbin receiving opening 2, the head 3 of the bobbin having usual annular projections or rings 4 thereon, and the jaws are held in the shuttle in any suitable manner, forming no part of our present invention, a transverse bolt 5, shown in dotted lines passing through the shuttle-wood and the shank portions of the 60 jaws.

Herein we have shown the jaws as separate, 70 and in practice made of resilient plate-metal, each jaw comprising a shank portion 6, a free end or bobbin-holding portion 7, and a reversely-bent connecting part 8, the shank portion having a hole 9, Figs. 2 and 3 for the 75 bolt 5. The shank portions are fixedly held in the shuttle-wood, the free end 7 of the jaws extending into the bobbin-receiving opening 2 in one end thereof, as usual.

In accordance with our invention the inner 80 faces of the free ends of the jaws are provided with opposite, upright grooves 10, 10^x, Figs. 2 and 3, the grooves 10 being longer and deeper than the grooves 10^x, as best shown in Fig. 3, the latter grooves being 85 nearer the reversely-bent portion 8. When the free ends of the jaws are separated by an incoming bobbin the greatest strain comes upon those grooves near the bases of the free ends of the jaws, but by making such grooves, 90 as 10^x, of less depth than the other grooves we increase the thickness of the metal at or near the point of greatest strain, and thereby increase the resistance to rupture when the jaws are flexed or spread. If the rings 4 on the incoming bobbin-head strike the upper edges of the jaws directly over the holding grooves the rings will pass down into the grooves, but if the rings strike at one side of 95 such grooves there is a tendency to improper positioning of the rings, so that the bobbin is not securely held. To overcome this we provide at the upper end of each groove a 100 guide-entrance 11, communicating with the groove and flared both outwardly and transversely, in a substantially inverted cone-shape, and symmetrically located with relation to the groove, that is, with the longitudinal axes of the groove and guide-entrance alined, so that when the rings strike 110

the walls of such entrances they will be directed thereby positively and accurately to the upper ends of the grooves, which communicate at 12, Fig. 2, with the small ends 5 of the guide-entrances. The symmetrical arrangement of the guide-entrances relatively to the grooves provides a smooth entrance of the rings into the grooves, even if they enter the guide-entrances at one or the 10 other side of their axes.

The entrances for the shallow grooves 10^x are in practice made of less depth than the entrances for the other grooves, to increase 15 the thickness of the metal, for the same reason that the grooves 10^x are made shallower than the other grooves. There are a sufficient 20 number of grooves to accommodate variations in the position of the shuttle when a bobbin is inserted, and to securely grasp 25 and hold the bobbin, while the shallower grooves will coöperate with one or more of the deeper grooves to hold the bobbin when, in extreme cases, it is inserted so far back from the tips of the jaws. Should the shallower 30 lower jaws be omitted altogether there would be nothing to effect a firm grasp upon the rings should the shuttle be materially out of place at the time of transfer, and warp breakage or other damage would result by reason of the faulty positioning and holding of the bobbin.

Having fully described our invention,

what we claim as new and desire to secure by Letters Patent is:—

1. A loom shuttle provided with a bobbin 35 receiving opening having resilient bobbin holding jaws mounted at one end thereof, the thickness of the material of said jaws decreasing from a point adjacent the end wall of the bobbin opening toward the end of said 40 jaws.

2. A loom shuttle provided with a bobbin receiving opening having resilient bobbin holding jaws mounted at one end thereof, 45 said jaws being provided with bobbin holding grooves, the grooves increasing in depth toward the ends of the jaws and the material of the jaws increasing in dimension toward the base of the jaws.

3. Bobbin holding means for loom shuttles, comprising resilient jaws having bobbin holding grooves, the grooves near the base of the jaws being of less dimension than those toward the end of the jaws and said grooves having guide entrances flaring toward the 50 end and base of the jaws.

In testimony whereof, we have signed our names to this specification, in the presence of two subscribing witnesses.

JONAS NORTHRUP.
EVERETT S. WOOD.
